YORK.

METAL-WORKING MACHINE.

1,241,257.

Specification of Letters Patent. Patented Sept. 25, 1917.

Application filed May 18, 1914. Serial No. 839,368.

To all whom it may concern:

Be it known that we, EDWARD V. WURTS and JOHN J. SWINBANK, citizens of the United States, residing at Pittsburgh, Pa., have made certain new and useful Improvements 5 in Metal-Working Machines, of which the following is a specification.

The invention relates to a metal punching machine and more especially to machines 10 for punching structural shapes in the process of fabrication. The objects and purposes of the invention will be set forth herein-after in part and in part will be obvious herefrom, and are realized and accomplished through the combination and instrumentalities set out in the appended claims.

The invention consists in the novel parts, constructions, arrangements, combinations and improvements herein shown and de- 20 scribed.

The accompanying drawings, referred to herein and forming a part hereof, illustrate one embodiment of the invention, and together with the description serve to illustrate the principles thereof.

Of the drawings:

Figure 1 is a front elevation of a machine constructed in accordance with the principles of the invention;

30 Fig. 2 is a central vertical section on the line A—B of Fig. 1, looking in the direction of the arrows, but with certain parts shown in elevation, and showing the punches open;

35 Fig. 3 is a view similar to Fig. 2 showing the punches through the beam or shape;

Fig. 4 is an elevation of the moving punch carrying frames removed from the machine frame, with parts in section and showing 40 the punch and die in the open position;

Fig. 5 is a view similar to Fig. 4 but showing the mechanism in punching position;

Fig. 6 is a fragmentary elevation of the 45 punch and die carrying frame shown in Figs. 4 and 5 viewed from the side.

Fig. 7 is a horizontal section on line E—F of Fig. 2;

Fig. 8 is a fragmentary view of the central 50 part of Fig. 1 showing a greater separation of the punches and dies;

Fig. 9 is a central section through the punch and die blocks on an enlarged scale, showing the adjustment therefor and showing 55 the gag operating mechanism;

Fig. 10 is a detail, on an enlarged scale, of the automatic control for the punch and die adjusting mechanism;

Fig. 11 is a section on the line C—D of 60 Fig. 10 and showing parts beneath; and

Fig. 12 is a fragmentary plan of the driving mechanism and control therefor;

Fig. 13 is a diagrammatic view of the controller sheet, and circuits and electro- 65 magnetic devices controlled thereby.

Referring to the accompanying drawings, illustrating by way of example one embodiment of the invention, means are provided for progressing or traveling the beam or shape through the machine and for successively stopping the shape relatively to the punching mechanism to locate the punched holes at the desired points or places in the beam. In such embodied form, the location of the punched holes longitudinally is 70 effected or determined by the longitudinal travel and stopping of the beam, and the transverse location of the holes, that is cross-wise of the beam, is effected by traveling the punching mechanism to and fro across 75 the beam.

In the embodied form, the means for longitudinally traveling and stopping the beam α comprises a substantially horizontally arranged series of rollers 1 upon which 80 the beam α is supported. Said rollers and the coöperating distance determining devices may be of the same general form as is shown in copending application Serial No. 824,386 filed March 13, 1914, and Ser. No. 814,380 filed January 26, 1914. The distance determining devices of the kind mentioned, comprise a head 2 which engages the forward end of the beam α to permit or prevent travel of the beam by the rotation 85 of rollers 1. The head 2 is attached to a rail or bar 3 extending horizontally backwardly alongside the beam α , said rail 3 being supported by a series of rollers 4. The rail 3 is connected to the distance de- 90 95 termining device proper (not shown).

Referring more particularly to the punching devices, they are supported in a frame having its bed or base 10 of general rectangular form and extending across the 100 path of travel of the beam. At either side said frame has upwardly extending supporting and guiding uprights 11, 12, 13 and 14. Mounted within and guided by said uprights is a supporting frame 9 for the 110

punches adapted to bring the punches and dies to center irrespective of the size of the beam and of the consequent variations in the height of the web from the rollers 1. 5 In accordance with certain features of the invention, the punches and the automatic centering means are mechanically operated, and in the embodied form said punch supporting frame has four vertically arranged members 15, 16, 17 and 18. In said upright members are formed vertical guideways into which project vertically disposed guides 19, 10 20, 21 and 22 formed on the corresponding uprights 11, 12, 13 and 14 of the machine frame. The vertically disposed members 15 and 16 are connected across at the bottom by a cross piece 23, and the corresponding members 17 and 18 are connected across at the bottom by a cross piece 24. The upright members 15, 16, 17 and 18 at their upper ends are all connected to a cap piece 25 extending between and connected to all 15 four of said vertically disposed members.

Thus the upright members 15, 16, 17 and 25 18, the bottom connecting pieces 23 and 24, and the cap piece or cross member 25 constitute a structure vertically movable to and fro in the upright guides 19, 20, 21 and 22. The upward movement of these parts 30 is limited by stops or projections 26 formed on the supporting and guiding uprights.

Journalized in the cross pieces 23 and 24 is a shaft 30. Within the cross pieces 23 and 24 said shaft has double crank arms 31 35 and 32, said double crank arms carrying therebetween a wrist pin or eccentric shaft 33. To rotate shaft 30, to one end of the shaft 30 exterior to the cross piece 23, is attached a flexible driving connection (later 40 described in detail) whereby said shaft is rotated irrespective of its up and down movement with the punch and die frame 19.

Means for restoring the punch and die frame are provided, and as embodied there 45 are within the upright frame members series of weights 35 and 36, preferably in duplicate at either side of the machine. Each set or series of weights, respectively, is suspended by rods 37 or 38 from cross heads 50 39 or 40, said weights acting or tending to move the slidable frame up to the stops 26 on the frame uprights. The cross heads 39 work on guides 41 and 42 at either side of the machine, and the cross heads 40 correspondingly work on guides 43 and 44, formed on the respective machine frame uprights. Connected to the respective cross heads 39 and 40 are pivoted links 45 and 55 46. The lower ends of the links 45 are pivotally connected to a lever 47 at one side of the machine, and likewise at the other side of the machine. The levers 47 are pivoted, respectively, at 48 upon brackets 49 on the machine frame. Likewise, the other ends of 60 65 the links 46 are pivotally connected to a

lever 50, fulcrumed at 51 upon a bracket 52 carried on the machine frame, and correspondingly at the other side of the machine. The other ends of the levers 47 and 50 are pivotally connected by links 53 to 70 the cross pieces 23 and 24.

The punches are carried on a punch carrier 60, working in guides 61 and 62, formed on the bottom side of the cross member or cap piece 25. The punches and 75 co-operating dies are traveled together along said cross member 25, to locate the rivet holes across or transversely in the shape or beam, the position of the rivet holes along or longitudinally of the shape being determined by the stopping of the shape by the head 2. The embodied form of devices for effecting such transverse movement of all the punch and die blocks together is later described in detail.

In the embodied form of means for providing the relative movement between the punches and dies to cause them to approach and recede from each other in the centering operation and the punching operation, in addition to the movement of the punch carrying frame, the die carrier is vertically reciprocable to and fro on said frame and relatively to the punch carrier. In the embodied form of such means a cross member, or die carrying cross head 64 is reciprocably mounted in pairs of corner guides 65 and 66 formed in the upright pieces 15, 16, 17 and 18. On the bottom of the cross head 64, and slidable to and fro in guides 100 formed in the bottom of the head 64, are bearing blocks 67 and 68. Said blocks 67 and 68 are cylindrically recessed upon the bottom side thereof to bear upon the eccentric portion 33 of shaft 30, thus following 105 the part 33 in its rotation, meanwhile sliding along the bottom of the cross member 64, and imparting only vertical motion thereto.

The manner of operation of the mechanism shown and described is substantially as follows:

The shape x is traveled along upon the rollers 1 until brought to rest automatically by the preliminarily set distance determining means through the action of the rail 3 and head 2.

When the shape x is properly positioned, the shaft 30 is permitted to rotate, and the punch carrying frame is drawn downwardly 120 and the die carrying cross member or head 64 is moved upwardly from the position shown in Fig. 4 to the position shown in Fig. 5. The transverse sliding movement between the bearing blocks 67 and 68 and 125 the cross head 64 permits the cross head 64 to move vertically while the bearing blocks 67 and 68 follow the eccentric crank or shaft 33 in its rotation. Thus the punches are brought against one side of the web of 130

the shape *a* and the die blocks against the other side of the web, irrespective of the height of the web from the tops of the rollers 1. During this movement the rotation 5 of the shaft 30 will draw the punch carrying frame downwardly, the levers 47 and 50 lifting the counterweights 35 and 36 correspondingly. The flexible connection from shaft 30 to its rotating means permits 10 of free movement of the punch carrying frame in the centering operation. When the punches and dies are brought firmly against the opposite sides of the web, the succeeding rotation of the shaft 30 and of 15 the eccentric shaft 33 will drive the punches through the web. As the part 33 passes over the upper extreme of its throw, and moves downwardly on the opposite side, the punches and dies will move apart, and the 20 punch carrying frame will move upwardly, by reason of the counterweights, until brought to rest against the stops 26. In the embodied form, the counterweights hold the punches up and also hold the gap between the punches and dies open to admit 25 the shape. The weight of the punches and coöperating parts, such as the supporting bar and movable frame and the unbalanced part of the shaft are slightly over-balanced 30 by the counterweights. On rotation of the shaft the punches 60 and the frame are drawn down, thus lifting the weights. When the punches meet the web of the beam, the downward movement stops, and the 35 pressure or purchase of the punches on the web makes a "heel" or fulcrum for lifting the floating shaft, the lower frame and the dies up to the shape. When the dies meet the beam this upward movement stops, and 40 the punches and parts move downwardly again, punching the holes. The counterweights assist the shaft in restoring all parts to initial position. There is thus provided a floating punch and die carrier 45 automatically centering itself for beams of different sizes and it is positively and mechanically driven to punch the work.

The embodied form of flexible drive for the shaft 30 comprises a flexible or universal joint 50 between the shaft 30 and a shaft 71. The shaft 71 has a universal joint 72 connecting with a shaft 73 journaled in a bearing 74.

Mounted on shaft 74 is a clutch member 55 75, which rotates with the shaft but is slideable thereon. Loose on shaft 73 is a gear wheel 76, said wheel being driven by a pinion 77 from a motor 78. The gear 76 has a clutch member 79 with which the 60 clutch member 75 is adapted to engage. A spring 80 impels clutch member 75 into engagement with clutch member 79.

Formed in the exterior of clutch member 75 is a cam groove 81, into which projects a 65 camming and releasing finger 82, which may

be spring pressed and operable in a suitable manner, as for instance manually, or it may be automatically operated from a distance record sheet by a solenoid 83. When the finger 82 is retracted from the groove 81 it 70 permits a single rotation of shaft 73 and thereby a rotation of shaft 30. Finger 82 moves back under the action of its spring into the wide portion of the slot or groove 81 to cam out the clutch member 75, and 75 thus to stop the shaft 30 after a single rotation thereof until the pin 82 is again retracted.

In the embodied form of means for traveling and positioning the punches and dies 80 transversely or across the beam, the punch carrying block 60, which is mounted to slide along cross member 25, is connected by an arm 90 to a cross piece 91. Arm 90 is slideable along cross piece 91 during the movement of the punch carrying frame. Connected to cross piece 91 at a central point is a screw threaded shaft 92, or other suitable connection to a distance determining means such as an automatically operating, preliminarily settable distance record device, an example of which is shown in copending application Serial No. 814,380 filed January 26, 1914.

The amount and direction of rotation of 95 the screw threaded shaft 92 will be determined by the distance determining device, which may be set or operated either by a keyboard or by a distance record sheet. The shaft 92 and the head 2 thus coöperate together to locate both longitudinally and transversely a hole or group of holes in the shape, and the same distance record sheet may control the degree of separation of the various holes in a group, as will be later 100 described.

Mounted upon the cross head or member 64 is the die carrying block 93 which is slideable along said member 64 and thus transversely to the shape as it is run through the 105 machine. Said die block 93 has a bracket arm 94 likewise connected to and vertically slideable on the cross piece 91. The corresponding punch and die block are thus moved together to and fro across or transversely to the work.

Means are provided in accordance with one feature of the invention for so traveling and positioning a plurality of punches and dies, transversely adjusting and positioning 110 one punch and its coöperating die with respect to another punch and its coöperating die to cause a greater or less separation of the rivet holes in a group in addition to positioning the group transversely to the 115 beam or shape.

In the embodied form of such means, four punches and their coöperating dies are shown, two of said punches and their dies being carried in fixed position upon the cor- 120 125 130

responding punch carrier 60 and die carrier 93, the other two punches and their dies being movably mounted on the carriers 60 and 93 and relatively to the two first mentioned punches and dies transversely of the beam or shape α .

In the embodied form, a punch carrying block 96 is fixed to the head 60, having therein a punch, or rather two punches 97, 10 which punches are provided respectively with shanks 98 and heads 99. Each of said punches are fixed to a plate 100, against which works a spring 101. The corresponding die block 102 has dies 103 corresponding 15 to the punches 97, the construction being the same. Mounted in the block 96 is a shaft 104 fixed against longitudinal movement but free to rotate. To the right of said block 96 (Fig. 8) shaft 104 has a screw thread 20 105 engaging an internal screw thread formed in a lug 106 on a punch block 107, which punch block is slidably mounted in the carrier 60. Said block 107 carries punches 108, which need not be described in 25 detail, the construction being preferably the same as the corresponding parts already described. Each punch is provided with a gagging device, preferably electro-magnetically operated. As embodied, gags 136 are 30 slidable into and out of operative relation with the corresponding punches 97 or 108. Fixed to each gag is a rod 137 connected to the core of a solenoid 138, which is impelled in the opposite direction from the action of 35 the solenoid by a spring 139.

The shaft 104 is mounted in a bearing 109 in the block or head 60. Fixed to the end of the shaft 104 is a bevel gear 110 meshing with a corresponding bevel gear 111, fixed to 40 a vertical shaft 112 carried by a bracket 113 mounted on punch frame 9, a bracket 114 mounted on die frame 64, and a bracket 115 mounted on the machine frame.

A die block 116 having dies corresponding 45 to the punches 108, is slidably mounted upon the carrier 93. A shaft 117 is rotatably mounted in the die block 102, and has an exteriorly screw-threaded portion 118 engaging an internal screw thread formed in 50 the lug 119 upon a slidable die block 116. Shaft 117 is journaled at 120 on the die carrying member 93. Said shaft has a bevel gear 121 engaging a bevel gear 122 splined upon the shaft 112. A suitable sliding connection or sleeved joint (omitted from the drawing for the sake of clearness) may be 55 formed in the shafts 104 and 117 to permit of the transverse travel and location, previously described, of the punches and dies by 60 the distance determining device through shaft 92.

The embodied form of actuating means for the mechanism just described comprises automatic devices for controlling same from

a distance record device such as is shown 65 in copending application Serial No. 814,380. In Fig. 13, the distance record sheet is shown diagrammatically at 140, with contacts 141, communicating through circuits 142, with the various solenoids, such as 83, 70 134 and 138, already described and shown in the preceding figures of the drawings, and indicated in Fig. 13. The switch 143 represents in Fig. 13 the alternative regulation for the punching and controlling devices, whereby they are brought into action 75 in proper timed relation with each other.

As embodied, shaft 112 has a bevel pinion 123 meshing with a bevel gear 124, fixed upon a shaft 125. Fixed to shaft 125 is a gear 126, meshing with a pinion 127 said pinion being driven by motor 128. Fixed to shaft 125 is a disk 130 carrying a detent lug 131. Surrounding shaft 125 is a ring 132, mounted on the machine frame, and having a plurality of apertures therein, in which apertures are reciprocably mounted stop pins 133 projectable into the path of the stop lug 131. Said pins are controlled and operated by springs 135 and solenoids 80 90 134, said solenoids being in circuits which are opened or closed by the distance record sheet 140.

The manner of operation of the mechanisms last described will be understood from the foregoing without further detailed description, as will also the manner of co-operation thereof with the mechanisms previously described.

From all the foregoing it will be understood that a machine has been provided realizing the objects and advantages herein set forth, together with other objects and advantages. It will also be understood that changes may be made from the particular 100 form of mechanism shown and described within the scope of the accompanying 105 claims, without departing from the principles of the invention and without sacrificing its chief advantages.

What we claim as our invention and desire to secure by Letters Patent, is:

1. A punching machine including in combination a punch carrying frame movable toward and from the work, a die carrying frame movable toward and from the work, a floating shaft having a single eccentric portion, the shaft and one of said frames moving together, and the other of said frames and the eccentric portion of said 110 shaft moving together.

2. A punching machine including in combination a punch carrying frame movable toward and from the work, a die carrying frame movable toward and from the work, a floating shaft having a single eccentric portion, the shaft being journaled in one of said frames, and the other of said frames 115 120 125

and the eccentric portion of the shaft moving together.

3. A punching machine including in combination a punch carrying frame movable toward and from the work, a die carrying frame movable toward and from the work, a floating shaft having a single eccentric portion, the shaft and one of said frames moving together and the other of said frames and the eccentric portion of said shaft moving together, and means for traveling and stopping the shape relatively to the punching mechanism.

4. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together, and means including an automatic distance determining device for traveling and stopping the shape relatively to the punching mechanism.

5. A punching machine including in combination a punch carrying frame movable toward and from the work, a die carrying frame movable toward and from the work, a floating shaft having a single eccentric portion, the shaft and one of said frames moving together, and the other of said frames and the eccentric portion of said shaft moving together, and means for causing relative movement of the punch and the shape transversely of the shape to correctly position the punched holes transversely of the shape.

6. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together and means, including a distance record device, for causing relative movement of the punch and the shape transversely of the shape to correctly position the punched holes transversely of the shape.

7. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together, and automatically operating means for causing relative movement of the punch and shape transversely of the shape to correctly position the punched holes transversely of the shape.

8. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together and devices for traveling the shape and stopping it relatively to the punching mechanism longitudinally and transversely.

9. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together, and devices including an automatic distance determining device for traveling the shape and stopping it relatively to the punching mechanism longitudinally and transversely.

10. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together and means including a preliminarily settable automatically operating device for traveling and stopping the shape relatively to the punching mechanism.

11. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together, a plurality of punches carried by said punch carrying frame and a plurality of dies carried by said die carrying frame, and means for varying the position of the respective sets of punches and dies relatively to each other.

12. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together, a plurality of punches carried by said punch carrying frame and a plurality of dies carried by said die carrying frame, and settable means for varying the position of the respective sets of punches and dies relatively to each other.

13. A punching machine including in com-

- bination a punch carrying frame movable toward and from the work, a die carrying frame movable toward and from the work, a shaft having an eccentric portion, the shaft, and one of said frames moving together, and the other of said frames and the eccentric portion of said shaft moving together, a plurality of punches carried by said punch carrying frame and a plurality of dies carried by said die carrying frame, and means operating electrically for varying the position of the respective sets of punches and dies relatively to each other.
14. A punching machine including in combination a punch carrying frame movable toward and from the work, a die carrying frame movable toward and from the work, a shaft having an eccentric portion, the shaft and one of said frames moving together, and the other of said frames and the eccentric portion of said shaft moving together, a plurality of punches carried by said punch carrying frame and a plurality of dies carried by said die carrying frame, and means including a distance record sheet and electrical connections therefrom for varying the position of the respective sets of punches and dies relatively to each other.
15. A punching machine including in combination a floating shaft having an eccentric portion, a punch carrying frame, a die carrying frame, one of said frames being carried to the work by the shaft and the other being carried to the work by the eccentric portion of the shaft.
16. A punching machine including in combination a floating shaft having an eccentric portion, a punch carrying frame, a die carrying frame, one of said frames being carried to the work by the shaft and the other being carried to the work by the eccentric portion of the shaft, and means for traveling and stopping the shape relatively to the punching mechanism.
17. A punching machine including in combination a floating shaft having an eccentric portion, a punch carrying frame, a die carrying frame, one of said frames being carried to the work by the shaft and the other being carried to the work by the eccentric portion of the shaft, rotating means, and a flexible connection therefrom to said shaft, means for traveling and stopping the shape relatively to the punching mechanism, said rotating means rotating said shaft while the shape is at rest.
18. A punching machine including in combination a shaft having an eccentric portion, a punch carrying frame, a die carrying frame, one of said frames being carried to the work by the shaft and the other being carried to the work by the eccentric portion of the shaft, and means operating automatically for traveling and stopping the shape relatively to the punching mechanism.
19. A punching machine including in combination a shaft having an eccentric portion, a punch carrying frame, a die carrying frame, one of said frames being carried to the work by the shaft and the other being carried to the work by the eccentric portion of the shaft and means, including a distance determining device for traveling and stopping the shape relatively to the punching mechanism.
20. A punching machine including in combination a shaft having an eccentric portion, a punch carrying frame, a die carrying frame, one of said frames being carried to the work by the shaft and the other being carried to the work by the eccentric portion of the shaft, and means including a preliminarily settable automatically operating distance determining device for traveling and stopping the shape relatively to the punching mechanism.
21. A punching machine including in combination a floating shaft having an eccentric portion, a punch carrying frame, a die carrying frame, one of said frames being carried to the work by the shaft and the other being carried to the work by the eccentric portion of the shaft, and means for causing relative movement between the punch and die and the shape to locate the perforations transversely in the shape.
22. A punching machine including in combination a shaft having an eccentric portion, a punch carrying frame, a die carrying frame, one of said frames being carried to the work by the shaft and the other being carried to the work by the eccentric portion of the shaft, and means including a distance determining device for causing relative movement between the punch and die and the shape to locate the perforations transversely in the shape.
23. A punching machine including in combination a shaft having an eccentric portion, a punch carrying frame, a die carrying frame, one of said frames being carried to the work by the shaft and the other being carried to the work by the eccentric portion of the shaft, a plurality of punches carried on one of said frames, a plurality of dies carried on the other of said frames and means for varying the distance between the respective sets of punches and dies.
24. A punching machine including in combination a shaft having an eccentric portion, a punch carrying frame, a die carrying frame, one of said frames being carried to the work by the shaft and the other being carried to the work by the eccentric portion of the shaft, a plurality of punches carried on one of said frames, a plurality of dies carried on the other of said frames, and settable means for varying the distance between the respective sets of punches and dies.

25. A punching machine including in combination a shaft having an eccentric portion, a punch carrying frame, a die carrying frame, one of said frames being carried to the work by the shaft and the other being carried to the work by the eccentric portion of the shaft, a plurality of punches carried on one of said frames, a plurality of dies carried on the other of said frames, and means including a distance record device for varying the distance between the respective sets of punches and dies.

26. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape, a die carrier movable on the other of said frames transversely of the shape and means for so moving said carriers together.

27. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape, a die carrier movable on the other of said frames transversely of the shape, and means including a distance determining device for so moving said carriers together.

28. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape and having a plurality of punches, a die carrier movable on the other of said frames transversely of the shape and having a plurality of dies and means for so moving said carriers together, and means for varying the distance between the respective sets of punches and dies.

29. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape, and having a plurality of punches, a die carrier movable on the other of said frames transversely of the shape and having a plurality of dies and means for so moving said carriers together and settable means for

varying the distance between the respective sets of punches and dies.

30. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape and having a plurality of punches, a die carrier movable on the other of said frames transversely of the shape and having a plurality of dies and means for so moving said carriers together, and means including a distance record device and devices settable thereby for varying the distance between the respective sets of punches and dies.

31. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape, and having a plurality of punches, a die carrier movable on the other of said frames transversely of the shape and having a plurality of punches and means including a settable automatically operating distance determining device for so moving said carriers together, and means for varying the distance between the respective sets of punches and dies.

32. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape and having a plurality of punches, a die carrier movable on the other of said frames transversely of the shape and having a plurality of punches and means for so moving said carriers together, and means operating automatically for varying the distance between the respective sets of punches and dies.

33. A punching machine including in combination a shaft having an eccentric portion, a punch carrying frame, a die carrying frame, one of said frames being carried to the work by the shaft and the other being carried to the work by the eccentric portion of the shaft, a punch carrier movable on one of said frames transversely of the shape and having a plurality of punches, a die carrier movable on the other of said frames transversely of the shape and having a plurality of dies and means for so moving said carriers together, and settable means

- for varying the distance between the respective sets of punches and dies.
34. A punching machine including in combination a shaft having an eccentric portion, 5 a punch carrying frame, a die carrying frame, one of said frames being carried to the work by the shaft and the other being carried to the work by the eccentric portion of the shaft, a punch carrier movable on one 10 of said frames transversely of the shape, and having a plurality of punches, a die carrier movable on the other of said frames transversely of the shape and having a plurality of punches and means including a distance 15 determining device for so moving said carriers together and means including a distance record device and devices settable thereby for varying the distance between the respective sets of punches and dies.
- 20 35. A punching machine including in combination upright guiding members, a frame vertically slidable on said guiding members, a floating shaft carried by said frame and having an eccentric portion, a second frame 25 slidable vertically relatively to said first mentioned frame and moving with the eccentric part of said shaft, a punch carried by one of said frames and a die carried by the other frame.
- 30 36. A punching machine including in combination upright guiding members, a frame vertically slidable on said guiding members, a floating shaft carried by said frame and having an eccentric portion, a second frame 35 slidable vertically relatively to said first mentioned frame and moving with the eccentric part of said shaft, a punch carried by one of said frames and a die carried by the other frame, rotating means, and a flexible connection between said rotating means 40 and said shaft.
37. A punching machine including in combination upright guiding members, a frame vertically slidable on said guiding members, 45 a shaft carried by said frame and having an eccentric portion, a second frame slidable vertically relatively to said first mentioned frame and moving with the eccentric part of said shaft, a punch carrier movable on one of said frames transversely to the shape, 50 a die carrier movable on the other of said frames transversely to said shape, and means for so moving said carriers together.
38. A punching machine including in combination upright guiding members, a frame vertically slidable on said guiding members, a shaft carried by said frame and having an eccentric portion, a second frame slidable vertically relatively to said first mentioned 55 frame and moving with the eccentric part of said shaft, a punch carrier movable on one of said frames transversely to the shape, a die carrier movable on the other of said frames transversely to said shape, and auto- 60 matically operating means for so moving said carriers together.
39. A punching machine including in combination upright guiding members, a frame vertically slidable on said guiding members, a shaft carried by said frame and having an eccentric portion, a second frame slidable vertically relatively to said first mentioned frame and moving with the eccentric part of 70 said shaft, a punch carrier movable on one of said frames transversely to the shape, a die carrier movable on the other of said frames transversely to said shape, and settable means for so moving said carriers together. 75
40. A punching machine including in combination upright guiding members, a stop, a frame vertically slidable on said guides, a weight impelling said frame against said stop, a shaft carried by said frame and having an eccentric portion, a frame vertically 80 slidable with respect to said first-mentioned frame and moving with the eccentric portion of said shaft, a punch carried by one of said frames and a die carried by the other of said frames. 85
41. A punching machine including in combination upright guiding members, a stop, a frame vertically slidable on said guides, a weight impelling said frame against said stop, a shaft carried by said frame and having an eccentric portion, a frame vertically 90 slidable with respect to said first-mentioned frame and moving with the eccentric portion of said shaft, a punch carried by one of said frames and a die carried by the other of said frames, rotating means for said shaft, and a flexible connection between said means and said shaft. 95
42. A punching machine including in combination upright guiding members, a stop, a frame vertically slidable on said guides, a weight impelling said frame to said stop, a shaft carried by said frame and having an eccentric portion, a frame vertically 100 slidable with respect to said first mentioned frame and resting upon the eccentric portion of said shaft, a punch carried by one of said frames and a die carried by the other. 105
43. A punching machine including in combination guiding members, a frame slid- 110 able on said guides, a shaft carried by said frame and having an eccentric portion, a second frame slidable on guides carried by said first frame, and moved by said eccentric part of said shaft, a punch carried by one of said frames and a die by the other. 115
44. A punching machine including in combination guiding members, a frame slid- 120 able on said guides, a shaft carried by said frame and having an eccentric portion, a second frame slidable on guides carried by said first frame, movable connections between said second frame and the eccentric 125

part of said shaft, a punch carried by one of said frames and a die by the other.

45. A punching machine including in combination guiding members, a frame slideable on said guides, a shaft carried by said frame and having an eccentric portion, a second frame slideable on guides carried by said first frame, slideable bearing blocks between said second frame and the eccentric part of said shaft, a punch carried by one of said frames and a die by the other.

46. A punching machine including in combination a frame comprising two substantially parallel members and a cross member, a shaft journaled in said parallel members away from said cross member and having an eccentric portion between said parallel members, a second cross member slideable on said parallel members to and from said first mentioned cross member and moved by said eccentric portion of said shaft, a punch carried by one of said cross members and a die by the other of said cross members.

47. A punching machine including in combination a frame comprising two substantially parallel members and a cross member, a shaft journaled in said parallel members away from said cross member and having an eccentric portion between said parallel members, a second cross member slideable on said parallel members to and from said first mentioned cross member, transversely slideable blocks between said second cross member and the eccentric portion of said shaft, a punch carried on one of said cross members and a die carried on the other of said cross members.

48. A punching machine including in combination a frame comprising two substantially parallel members and a cross member, a shaft journaled in said parallel members away from said cross member and having an eccentric portion between said parallel members, a second cross member slideable on said parallel members to and from said first mentioned cross member and moved by said eccentric portion of said shaft, a punch carried by one of said cross members and a die by the other of said cross members, and means for traveling said punch and die together along said cross members.

49. A punching machine including in combination a frame comprising two substantially parallel members and a cross member, a shaft journaled in said parallel members away from said cross members and having an eccentric portion between said parallel members, a second cross member slideable on said parallel members to and from said first mentioned cross member and moved by said eccentric portion of said shaft, a plurality of punches carried by one of said cross members, a plurality of dies carried by the other of said cross members, and means for vary-

ing the distance between the various sets of punches and dies.

50. A punching machine including in combination a frame comprising two substantially parallel members and a cross member, a shaft journaled in said parallel members away from said cross members, a shaft journaled in said parallel members away from said cross members and having an eccentric portion between said parallel members, a second cross member slideable on said parallel members to and from said first mentioned cross member, a plurality of punches carried by one of said cross members, a plurality of dies carried by the other of said cross members, and means for varying the distance between the various sets of punches and dies, and means for moving said plurality of punches and dies together along said cross members.

51. A punching machine including in combination a frame comprising two substantially parallel members and a cross member, a shaft journaled in said parallel members away from said cross members and having an eccentric portion between said parallel members, a second cross member slideable on said parallel members to and from said first mentioned cross member and moved by said eccentric portion of said shaft, a plurality of punches carried by one of said cross members, a plurality of dies carried by the other of said cross members, and means including a distance determining device for varying the distance between the various sets of punches and dies and means including a distance determining device for moving said plurality of punches and dies together along said cross members.

52. A punching machine including in combination vertical guiding members, a frame comprising substantially parallel members vertically slideable on said guiding members, a shaft journaled in said parallel members away from said cross member and having an eccentric portion between said parallel members, a second cross member slideable on said parallel members to and from said first mentioned member and moved by said eccentric portion of said shaft, a punch carried by one of said cross members and a die by the other of said cross members.

53. A punching machine including in combination vertical guiding members, a frame comprising substantially parallel members vertically slideable on said guiding members, a shaft journaled in said parallel members away from said cross member and having an eccentric portion between said parallel members, a second cross member slideable on said parallel members to and from said first mentioned cross member, slideable blocks between said second cross

- member and the eccentric portion of said shaft, a punch carried on one of said cross members and a die carried on the other of said cross members.
- 5 54. A punching machine including in combination vertical guiding members, a frame comprising substantially parallel members vertically slidable on said guiding members, a shaft journaled in said parallel members away from said cross member and having an eccentric portion between said parallel members, a second cross member slidable on said parallel members to and from said first mentioned member and moved by said eccentric portion of said shaft, a punch carried by one of said cross members and a die by the other of said cross members, a stop and a weight impelling said frame to said stop.
- 10 55. A punching machine including in combination vertical guiding members, a frame comprising substantially parallel

members vertically slidable on said guiding members, a shaft journaled in said parallel members away from said cross member and having an eccentric portion between said parallel members, a second cross member slidable on said parallel members to and from said first mentioned cross member and moved by said eccentric portion of said shaft, a punch carried by one of said cross members and a die by the other of said cross members, a rotating device, and flexible connections between said rotating device and said shaft.

25

In testimony whereof, we have signed our names to this specification, in the presence of two subscribing witnesses.
